FLUID CONTROL SYSTEM

William V. Sauter and Howard F. Lawrence,
Philadelphia, Pa., assignors to American Engineering Company, Philadelphia, Pa., a corporation of Pennsylvania

Original application May 18, 1935, Serial No. 22,217. Divided and this application June 16, 1938, Serial No. 213,989

6 Claims. (Cl. 137—152)

This application is a division of our co-pending application Serial No. 22,217, filed May 18, 1935, now Patent No. 2,173,884, granted Sept. 26, 1939, and the invention herein involved relates more particularly to automatically operable damper mechanisms associated with the tuyère blocks of stoker furnaces.

It is the primary object of the present invention to provide an improved flow control damper for use in fluid control systems for stoker furnaces.

Other and further objects will become apparent as the description of the invention progresses.

Of the drawing, Fig. 1 is a longitudinal sectional view taken through one of the retorts of a stoker furnace.

Fig. 2 is a side elevational view partly in section of a plurality of tuyère blocks showing the fluid control elements associated therewith in open position.

Fig. 3 is a similar view showing the fluid control elements in closed position; and

Fig. 4 is a plan view, partly in section and with parts broken away, of a pair of superimposed tuyère blocks showing a damper element mounted on one of said tuyère blocks.

Referring to the drawing, the numeral 1 designates a stoker of the underfeed type having alternately disposed retorts 2 and tuyère rows 3. Fuel is supplied to retorts 2 from a hopper 4, and any suitable feeding device driven by a power mechanism indicated at 5 feeds the fuel gravitating in hopper 4 to the retorts 2. A series of pushers 6 mounted in the bottom of each retort 2 is also operated by the power mechanism 5 through the connections 7. These pushers underfeed the fuel along the retorts and tuyères to an extension grate 8, which in turn overfeeds the fuel to an ash pocket 9 disposed at the rear of the stoker.

It is to be understood that the invention hereinafter described is not to be limited to its application to underfeed stokers, since it is equally adaptable for use in connection with other types of stokers, as well as other apparatus wherein flow control is desired.

When the terms "front" and "rear" are hereinafter used in connection with the description of the elements of the stoker 1 and the associated fluid control, it will be understood that the portions of such parts extending toward the rear or ash pocket 9 of the stoker will be designated as "rear", and those portions thereof extending toward the front or driving mechanism 5 of the stoker will be designated as "front".

Referring more particularly to Figs. 1 and 2, each tuyère row 3 comprises a series of superimposed tuyère blocks 10, each having a rounded nose or rear portion 11, and a substantially rectangular front portion 12. The upper surface 13

of each tuyère block is substantially flat and has a slightly beveled portion 14 extending around the nose portion thereof.

The tuyère blocks 10 are supported in the usual manner upon the side plates 15 of adjacent retorts 2. The forwardly disposed ends 16 of the tuyère blocks 10 extend between adjacent side plates 15. Draft air enters the tuyère blocks from a common pressure or plenum chamber 17 disposed beneath the stoker, which in turn is supplied with air from any suitable fan mechanism (not shown) in a well known manner.

The mechanism for controlling the flow of fluid from plenum chamber 17 to the tuyère blocks 10 comprises a series of independently operable damper elements 18, one for each of said tuyère blocks 10.

As shown in Figs. 2 and 3, each damper element 18 is of arcuate construction. The forwardly disposed end of each damper 18 is bent in the form of a loop, as shown at 19, and a pin 20 extending through said loop pivotally supports the damper in position. The pin 20 extends through apertures provided in the forwardly extending projections 21 of the associated tuyère block 10. As shown in Fig. 2, the rearwardly disposed end of each damper 18 rests upon the upper surface of the associated tuyère block 10, and extends between the ribs 22 of the next higher tuyère block of the series forming the inlet passage 23 thereof. These dampers operate on the airfoil principle and function when the velocity of the air passing thereover reaches a predetermined value to produce the necessary reduction in pressure thereabove to cause the damper elements to move upwardly, as shown in Fig. 3, and thereby close the inlet passages 23 of the tuyère blocks and thus partially or completely shut off the air supply to the fuel bed overlying such tuyère blocks. In order to retain these damper members in open position until the air flowing through the tuyère blocks reaches a predetermined velocity, the damper elements 18 may be provided with weights W at the rearwardly disposed ends thereof, or the material of which the dampers are constructed may be sufficiently heavy to function in the desired manner. When the dampers 18 are in closed position, as shown in Fig. 3, a slight air leakage occurs past the upper surfaces thereof and accordingly the lifting effect thereon is maintained. As a result the dampers remain in closed position until the condition of the fuel bed changes to impose a greater resistance to the flow of air through the associated tuyère blocks.

It will also be noted that the dampers are disposed substantially longitudinally in respect to the direction of air flow to the tuyère blocks, and accordingly the impact head of the air flowing past the dampers has little or no effect upon the operation thereof.

From the foregoing description it is apparent that our fluid control mechanism is not only of simple construction, but is highly efficient in operation. Due to the simplicity of this construction, the dampers may be readily assembled on the tuyère blocks, and when once assembled in position they require no field adjustments, nor periodic attention by the operation of the stokers. By employing a fluid control mechanism of this character the maintenance cost of the stoker is materially reduced, since the dampers operate automatically, when fuel bed resistance increases to a dangerous extent to shut off the air supply to the tuyère blocks and thus immediately reduce the combustion rate at such points. The fuel feeding elements may then feed additional fuel to such portions of the fuel bed before the incandescent fuel has had the opportunity to cause any serious damage to the tuyère blocks. Blow holes which often occur in furnaces are thus practically eliminated by the use of the present invention.

While the embodiment herein shown is admirably adapted to fulfill the objects primarily stated, it is to be understood that it is not intended to limit the invention thereto, since it may be embodied in other forms, all coming within the scope of the claims which follow.

What is claimed is:

1. A damper adapted to control the flow of fluid in a passage, said damper being pivoted at one end thereof and so arranged that when in fully open position lies adjacent one wall of said passage, said damper having one surface thereof in contact with the fluid flowing through said passage, the said surface of the damper in contact with the fluid being so constructed and disposed that an area of low pressure is created on said surface when fluid is moving in said passage, the pressure so produced being in inverse proportion to the velocity of the fluid flowing in said passage, whereby when the velocity of the fluid reaches a predetermined value, the difference in pressures operating at the opposite sides of said damper will cause it to move toward closed position to throttle the flow of fluid in said passage.

2. A damper adapted to control the flow of fluid in a passage, said damper being pivoted at one end thereof and so arranged that when in fully open position lies adjacent one wall of said passage, said damper having one surface thereof in contact with the fluid flowing through said passage, the said surface of the damper in contact with the fluid being so constructed and disposed that an area of low pressure is created on said surface when fluid is moved in said passage, the pressure so produced being in inverse proportion to the velocity of the fluid flowing in said passage, whereby when the velocity of the fluid reaches a predetermined value, the difference in pressures operating at the opposite sides of said damper will cause it to move toward closed position to throttle the flow of fluid in said passage, and weight means secured to said damper for holding the latter in open position until the fluid flowing in said passage reaches a predetermined velocity.

3. A damper adapted to control the flow of fluid in a passage, said damper being pivoted at

one end thereof and so arranged that when in fully open position lies adjacent one wall of said passage, said damper having a convex surface exposed to the fluid flowing in said passage, said convex surface being so disposed that an area of low pressure is produced thereon when fluid is flowing in said passage, the said pressure so produced being in inverse proportion to the velocity of the fluid passing thereover, whereby when the velocity of the fluid reaches a predetermined value the difference in pressures operating at the opposite sides of said damper will cause said damper to move toward closed position to throttle the flow of fluid in said passage.

4. A damper adapted to control the flow of fluid in a passage, said damper being pivoted at one end thereof and so arranged that when in fully open position lies adjacent one wall of said passage, said damper being substantially longer than the distance between the walls of the passage from and toward which it moves, and having a convex surface exposed to the fluid flowing in said passage, and said convex surface being so disposed that an area of low pressure is produced thereon, the said pressure so produced being in inverse proportion to the velocity of the fluid passing thereover, whereby when the velocity of the fluid reaches a predetermined value the difference in pressures operating at the opposite sides of said damper will cause it to move toward closed position to throttle the flow of fluid in said passage.

5. A damper adapted to control the flow of fluid in a passage, said damper being pivoted at one end thereof and so arranged that when in fully open position lies adjacent one wall of said passage, said damper being longer than the distance between the walls of said passage from and towards which it moves and having an arcuate surface over which the fluid flowing in said passage passes, and said arcuate surface being so disposed that an area of low pressure is produced thereon, the said pressure so produced being in inverse proportion to the velocity of the fluid passing thereover, whereby when the velocity of the fluid reaches a predetermined value the difference in pressures operating at the opposite sides of said damper will cause it to move toward closed position to throttle the flow of fluid in said passage.

6. A damper adapted to control the flow of fluid in a passage, said damper being pivoted at the upstream end thereof and so arranged that when in fully open position lies adjacent one wall of said passage, said damper being substantially longer than the distance between the walls of said passage from and toward which it moves, said damper having a convex surface exposed to the fluid flowing in said passage, and said convex surface being so disposed that an area of low pressure is produced thereon, the said pressure so produced being in inverse proportion to the velocity of the fluid passing thereover, whereby when the difference in pressures operating at the opposite sides of said damper is sufficient to overcome the weight thereof said damper will move toward closed position to throttle the fluid in said passage.

7. A damper adapted to control the flow of fluid in a passage, said damper being pivoted at the upstream end thereof and so arranged that when in fully open position lies adjacent one wall of said passage, said damper being substantially longer than the distance between the walls of said passage from and toward which it moves, said damper having a convex surface exposed to the fluid flowing in said passage, and said convex surface being so disposed that an area of low pressure is produced thereon, the said pressure so produced being in inverse proportion to the velocity of the fluid passing thereover, whereby when the difference in pressures operating at the opposite sides of said damper is sufficient to overcome the weight thereof said damper will move toward closed position to throttle the fluid in said passage.
